NEW COMPOSITION OF MATTER

Melvin De Groot, St. Louis, and Bernhard Keiser,
Webster Groves, Mo., assignors to Tretolite
Company, Webster Groves, Mo., a corporation
of Missouri

No Drawing. Application December 31, 1934,
Serial No. 760,025

3 Claims. (Cl. 87—12)

This invention relates to a new unsaturated, sulfonatable fatty body and to a method of producing the same.

One object of our invention is to provide a new material, composition of matter or chemical compound, that is capable of various industrial uses, but particularly adapted for use as a raw material in the manufacture of various sulfonated products intended to be used for the purpose for which ordinary Turkey red oils and similar materials are employed. Said new material, composition of matter or chemical compound may properly be described as a sulfonatable fatty acid, or glycerides thereof, having less than 16 carbon atoms and more than 5 carbon atoms in the molecule, and derived by the pyrolytic or thermal decomposition or splitting of a body obtained by oxidation of a relatively highly unsaturated non-hydroxylated fatty body. It is akin to hendecenoic or its glycerides and may be considered as an isologue or homologue of hendecenoic acid or its glycerides.

Hendecenoic acid or undecylenic acid, as it is sometimes termed, is obtained by distilling ricinoleic acid or the glyceride thereof (castor oil) under diminished or atmospheric pressure. The method of producing this acid is well known and is described in the publication "Dictionary of Applied Chemistry", by Thorpe, 1922. In volume 4, pages 630 and 631 of the said publication, the reaction of hendecenoic acid is properly indicated as follows:

but in the text the term "hendecatoic acid" is erroneously used to refer to the product $C_6H_{20}O_2$. However, volume 3, page 515 of the said publication properly identifies hendecatoic acid as "undecylic acid" ($C_6H_{20}O_2$). In other words, the pyrolytic decomposition of ricinoleic acid or castor oil causes the molecule to break at the hydroxyl position, and yields a sulfonatable unsaturated "fatty" acid having 11 carbon atoms. It is understood that the expression "fatty" is here used because the split acid thus obtained is a lower homologue of oleic acid. However, so far as we are aware, this acid does not occur naturally in any fat or oil, as is true of fatty acids in the usual sense. We will herein refer to hendecenoic acid derived from castor oil as "normal" hendecenoic acid.

U. S. Patent No. 1,749,463, to Bertsch, dated March 4, 1930 relates to the sulfonation of certain pyrolytic decomposition products of castor oil, which are known, in view of the above men-

tioned publication by Thorpe, to consist essentially of hendecenoic acid or a glyceride thereof. The value of normal hendecenoic acid as a raw material for producing valuable sulfonated products, is well recognized, in view of said Bertsch patent. The ability of castor oil or its acid, ricinoleic acid, to undergo thermal or pyrolytic decomposition so as to yield a sulfonatable fatty acid or glyceride of lower molecular weight, is unique. This property does not appear to be enjoyed by any other commercially available natural fat or fatty oil. As indicated by the reaction referred to above, it appears that decomposition takes place at the hydroxyl radical and that the fatty acid or glyceride thereof which is split off, contains the ethylene linkage, and thus is capable of sulfonation, although presumably the presence of an hydroxyl radical would give the same effect. The sulfonation of such material is described not only in the Bertsch patent previously referred to, but also in our co-pending application for patent Serial No. 760,024, filed December 31, 1934.

Due to the relatively high cost of castor oil, and also to the fact that the pyrolytic decomposition reaction yields an aldehyde and perhaps some hydrocarbon of limited commercial value, normal hendecenoic acid is somewhat expensive, and then even though valuable sulfonated products may be derived therefrom, the cost of the latter is markedly higher than the cost of ordinary Turkey red oils or substitutes therefor. We have attempted to produce materials similar in chemical properties to hendecenoic acid or its ester, and in such a manner that the products so obtained will compare favorably in cost with ordinary fatty materials employed in sulfonation processes, or for other purposes. The new composition of matter herein described may be used in the form of an acid, salt or ester to break petroleum emulsions of the water-in-oil type.

In producing our new material or composition of matter, we employ a relatively highly unsaturated fatty body as the raw material. By relatively highly unsaturated body we mean those materials whose iodine number is distinctly higher than oleic acid, and are thus characterized as having more than one ethylene linkage present in the hydrocarbon chain of the characteristic fatty acid or acids present as such or in the form of glycerides. It is well known that various drying and semi-drying oils, and various marine oils are characterized by an iodine number greatly in excess of oleic acid, varying in a general manner from approximately 120 to 180 or 190, com-

pared with a value of 80 to 90 for oleic acid or its glyceride.

When an unsaturated fatty acid or oil, for instance, oleic acid, is blown or oxidized with air, hydroxyl groups are formed at the ethylene linkage. This is particularly true if oxidation is carried out with moist air. It is believed that oxygen is first absorbed so as to saturate the ethylene linkage, and that further reaction takes place with water to produce two hydroxyl groups. Whether or not this is the correct explanation, it is known that hydroxyl groups are formed. For instance, "Chemistry of the Oil Industry", by Southcombe, 1926, page 181, in speaking of blown (oxidized) oils, states as follows:

"Hydroxyl groups are unquestionably formed, as the considerable rise in acetyl value proves."

If one uses air or oxygen to blow a fatty material having a single ethylene linkage, the resultant hydroxylated body has no particular analogy to ricinoleic acid, but is analogous, perhaps, to hydroxystearic acid. We have found by blowing a relatively highly unsaturated fatty acid or oil of the kind previously referred to, that the resultant product is characterized by the presence of fatty bodies having both a hydroxyl radical and an ethylene linkage. These particular materials are analogous to castor oil and may be subjected to thermal or pyrolytic decomposition in the same manner that castor oil or ricinoleic acid is subjected. The resultant product obtained, i. e., an unsaturated fatty acid or glyceride, having fewer carbon atoms, of course, than the original fatty body from which it is derived, is a cheap and suitable substitute for hendecenoic acid or its glycerides. There is, of course, an aldehyde, such as heptaldehyde (heptoic aldehyde) or somewhat similar bodies formed which may be used for the same purpose as heptaldehyde. For instance, these aldehydes may be combined with bisulfites, such as sodium or potassium bisulfites, to produce addition products having the same valuable properties enjoyed by heptaldehyde sodium bisulfite addition products. For instance, "Watts Dictionary of Chemistry" (1919) Muir and Morley, volume 2, page 680, contains the following in regard to heptoic aldehyde bisulfite addition products:

"Combinations with sulfites. The combinations with bisulfites of the alkalis may be obtained directly, or by passing SO_2 into an alcoholic solution of heptoic aldehyde containing potash, soda, or NH_3 .— $C_6H_{13}CH(OH)SO_3Na$ aq; brilliant unctuous scales; v.sol.water,v.e.sol. hot, nearly insol. cold, alcohol."

The aldehydes obtained in the manufacture of our new composition of matter, whether composed of heptoic aldehyde alone or similar materials or a mixture, may be employed in the same manner as pure heptoic aldehyde to produce bisulfite addition products.

It is not intended to infer that the use of hendecenoic acid is limited to its use as a raw material in sulfonation processes. The ammonium salt is available commercially and suited for certain particular purposes, for instance, where a soap-like body must be used in presence of large amounts of an electrolyte, such as salt. Likewise, the unsaturated acids herein described may be converted into the salts, etc. for similar purposes.

We desire to point out that the position of the ethylene linkages in various highly unsaturated fatty oils or acids may vary and that, due to variation in condition of oxidation, various ethylene linkages may be oxidized to produce hydroxyl

radicals, so that the unsaturated acid obtained by pyrolytic decomposition, may vary in molecular size, depending, in part, upon the position of the split hydroxyl radical. Thus, one may obtain various unsaturated acids having a different number of carbon atoms as a result of the process herein described. In some instances it is even possible that the split fatty acids may have a hydroxyl group attached to the hydrocarbon chain. These split acids appear to be homologues or isologues of oleic acid. The lowest homologue of oleic acid which is known to occur naturally, appears to be tiglic acid, which has four carbon atoms. Lower homologues of oleic acid having 6 to 10 atoms appear to be unknown in natural oils. The lower homologue of oleic acid, hendecenoic acid, previously referred to, is obtained most conveniently by the pyrolytic decomposition of castor oil. Also homologues of oleic acid, said to have 12 to 14 carbon atoms, have sometimes been stated to occur in the fat of cochineal; if this be true, they are only laboratory curiosities and are unknown commercially or in the trade. We have characterized our new composition of matter as containing more than five carbon atoms and less than 16 carbon atoms and being derived by the thermal or pyrolytic decomposition of oxidized (blown) relatively highly unsaturated fatty bodies, so as to clearly define the metes and bounds of our present invention. It is substantially free from or does not contain an appreciable amount of hendecenoic acid of the kind obtained from castor oil.

Since the blowing (oxidation) of various oils is a well known commercial process, and since the thermal decomposition of castor oil is a well known process, it is hardly necessary to give an elaborate description of a procedure suitable for producing our new composition of matter, in view of what has been said previously as to the necessary chemical reactions involved. Briefly stated, a suitable procedure consists simply of selecting a suitable, relatively highly unsaturated oil or acid, or mixture of the same, blowing said oil, acid or mixture with dry, or preferably, moist air or with any other suitable oxidizing agent, so as to produce a hydroxylated or oxy unsaturated material in which there are present substances having both a hydroxyl radical and an ethylene linkage present in the same hydrocarbon chain, and then subjecting this oxidized (oxy) unsaturated material to pyrolytic or thermal decomposition in the manner employed for the thermal decomposition of castor oil. The usual procedure is to heat to approximately 270 to 330° C., with a loss in weight of not over 12% under atmospheric or diminished pressure.

We prefer to use marine oils as a raw material on account of their low cost, and we particularly prefer to use American sardine oil, because it is frequently available at a cost of approximately one-half or less of the cost of castor oil. We prefer to conduct the blowing process and the thermal decomposition in the same vessel, purely as a matter of convenience. Our preferred procedure involves using 500 or 1,000 lbs. of sardine oil, and blowing the same with moist air at approximately 150 to 250° C. until there is a drop in iodine number to approximately $\frac{1}{2}$ or $\frac{1}{4}$ of the original iodine value, and a rise in acetyl value or absorption of oxygen corresponding to the drop in the iodine value. At the completion of the blowing process the moist air is shut off and the temperature raised with slightly reduced pressure, so as to thermally decompose the oxidized sardine

oil. The aldehyde-like materials which distill over, are condensed and employed for any suitable purpose. The loss in weight of the residue during thermal decomposition should not exceed, as a rule, 10% or 12% by weight of the original oxidized sardine oil. The final product which appears to represent homologues or isologues of oleic acid, but not to contain any hendecenoic acid, may be saponified in any suitable manner, so as to give salts suitable for use in the same manner that ammonium salt of normal hendecenoic acid is employed. As previously indicated, such materials may be employed in resolution of petroleum emulsions. If desired, the unsaturated materials obtained, may be sulfonated in the manner described in U. S. patent to Bertsch, previously referred to, so as to yield valuable products which may be employed for various purposes in the same manner that Turkey red oil is employed. It is to be noted that it is immaterial whether the final product be an acid or ester, or whether it be converted into a water-soluble salt, such as the sodium salt, or a water-insoluble salt, such as the calcium salt. It is immaterial whether the raw material prior to oxidation be an acid, or whether it be a naturally-occurring ester, such as sardine oil.

Since the exact decomposition of the materials herein contemplated is not known, but since they appear to be isologues or homologues of hendecenoic acid, and exhibit the property of an unsaturated fatty acid, such as hendecenoic acid, said materials may properly be designated by the coined term "isohomohendecenoic acids."

Having thus described our invention, what we claim as new and desire to secure by Letters Patent is:

1. A new composition of matter, consisting of an unsaturated, saponifiable, fatty acid material having at least 6 carbon atoms and less than 16 carbon atoms in the molecule and derived by thermal decomposition of a body obtained by oxidation of a relatively highly unsaturated fatty body; said fatty body, prior to oxidation, being charac-

terized by an iodine number of not less than 120 and not more than 190, said oxidation being conducted at a temperature range of from 150° C. to 250° C., by means of air until there is a drop in the iodine number to a value of not over two thirds the original iodine number and a corresponding increase in the acetyl value; and said thermal decomposition being conducted at a temperature range of from 270° C. to 330° C., with a loss in weight of not over 12%.

2. A new composition of matter, consisting of an unsaturated, saponifiable, fatty acid material having at least 6 carbon atoms and less than 16 carbon atoms in the molecule and derived by the thermal decomposition of a body obtained by oxidation of a relatively highly unsaturated fatty glyceride; said fatty glyceride, prior to oxidation, being characterized by an iodine number of not less than 120 and not more than 190, said oxidation being conducted at a temperature range of from 150° C. to 250° C., by means of air until there is a drop in the iodine number to a value of not over two thirds the original iodine number and a corresponding increase in the acetyl value; and said thermal decomposition being conducted at a temperature range of from 270° C. to 330° C., with a loss in weight of not over 12%.

3. A new composition of matter, consisting of an unsaturated, saponifiable, fatty acid material having at least 6 carbon atoms and less than 16 carbon atoms in the molecule and derived by thermal decomposition of a body obtained by oxidation of sardine oil, said oxidation being conducted at a temperature range of from 150° C. to 250° C., by means of air until there is a drop in iodine number to a value of not over two-thirds the original iodine number and a corresponding increase in the acetyl value; and said thermal decomposition being conducted at a temperature range of from 270° C. to 330° C., with a loss in weight of not over 12%.

MELVIN DE GROOTE.
BERNHARD KEISER.
